T. A. STEINMETZ

VALVE

Filed July 16, 1927

UNITED STATES PATENT OFFICE.

THEODORE A. STEINMETZ, OF ST. CLOUD, MINNESOTA.

VALVE.

Application filed July 16, 1927. Serial No. 206,261.

- This invention relates to a valve for wind instruments, particularly horns. The invention is not confined to the valve only, but resides also in the construction whereby cooperation of several such valves may be obtained and whereby such valves may be applied to a horn or other musical instrument. The valve may also be used generally in the mechanics arts.
- 10 Referring now to the drawings, Fig. 1 shows a side elevation of a fragment of a horn having three of my valves mounted thereon in co-operative relation.
- Figure 2 is an end elevation in section taken along the line 2—2 of Fig. 1, and
- 15 Figure 3 is a perspective view of one of the valves.
- Referring now to Figs. 2 and 3, 1 indicates an outer cylindrical casing and 2 an inner cylindrical casing closely fitting the outer one and rotatable therein. The outer casing is preferably a drawn or spun piece of metal closed as to one end except for two openings therein, while the inner piece may be a casting.
- 20 The inner cylinder has four openings in its front face and two in its rear, the two rear openings registerable with those of the casing.
- Thus there are two passages 3 and 3^a extending completely thru the cylinder when register
- 25 is accomplished and one passage 4 which alters its direction in the cylinder and emerges from the same face into which it entered.
- From the central axis of the inner case a shaft emerges on both sides thereof, the portion emerging and the front face being designated 5 and bearing a squared portion 5^a, that portion emerging from the rear being designated 6. A screw 7 and screw hole therefor is provided in the end of the shaft 5^a to hold
- 30 lever links 8, shown in Figs. 1 and 2 in dotted lines. Such lever links are actuated by stems which terminate in keys 10 (see Fig. 1) at the top of the horn. Such stems 9 are provided with retracting springs 11 in the usual manner so that after release of finger pressure on the keys, these resume their usual position. Full pressure on the keys will produce a quarter revolution of the inner casing the outer one remaining stationary. The effect of this
- 35 will be in the construction shown in Fig. 1 to change the position of the openings 4, throwing these out of register and throwing the openings 3 and 3^a into register with the holes in the stationary casing and with the openings of the crooks 12. It will then be evident
- that air blown into the horn will take a longer path, that is, through the crook 12 instead of being short circuited through the passage 4, thereby producing a different tone.
- In Fig. 1, it will be seen that three valves are utilized and that three changes of path of the air current are possible. Each key 10 controls one valve so that the resonating column of air behind the valve in the crooks 12 may be joined or cut off from the main resonating columns extending to the mouthpiece and to the bell of the horn. It will be seen that when the valve stems are not depressed, that the passages 4 of each of the valve bodies communicate with each other to form a curved continuous passage joining the tube to the mouthpiece and the tube to the bell. Three major changes in the timbre of the horn are therefore possible with the construction shown. It is obvious, of course, that instead of a construction utilizing three valves there may be any suitable number of valves used, either more or less than three. It is also permissible to utilize other known species of valves in a horn or other instrument employing one or more of my valves.
- Having described my invention, I claim:
1. In a valve, a cylindrical body having therein three passages, two of which are straight and extend through the said body and the third of which bends inside the body and makes its exit from the same face at which it enters, a casing for said body, one end of which is closed except for two holes registerable with the straight passages, and one hole to receive a bearing shaft on the body, and means for revolving the body inside the casing.
2. In a valve, a cylindrical body having therein three passages, two of which are straight and extend completely through the said body and the third of which is curved inside the body and makes its exit from the same face of the said body at which it entered, a bearing shaft at the central axis of the said body, a closely fitting casing for the said body, the said casing being open at one end and closed at the other except for two holes registerable with the straight passages through the body and a hole to receive the bearing shaft, and lever means to rotate the valve body in the casing.
3. In a valve, a cylindrical body having therein three passages, two of which are straight and extend completely through the

said body and the third of which is curved inside the body and makes its exit from the same face of the said body at which it entered, a bearing shaft at the central axis of the said body, a closely fitting casing for the said body, the said casing being open at one end and closed at the other except for two holes 50 registerable with the straight passages through the body and a hole to receive the bearing shaft, and lever means to rotate the valve shaft, and lever means to rotate the valve body in the casing, a squared portion on the bearing shaft adapted to cooperate with a square hole in one of the levers whereby a connection between the lever and the valve 10 body may be established.

4. In a valve, a cylindrical body having therein three passages, two of which are straight and extend completely through the said body and the third of which is curved 20 inside the body and makes its exit from the same face of the said body at which it entered, a bearing shaft at the central axis of the said body, a closely fitting casing for the said body, the said casing being open at one end and closed at the other except for two holes 25 registerable with the straight passages through the body and a hole to receive the bearing shaft, and lever means to rotate the valve body in the casing, through an angle 30 of 90°.

5. In a valve, a cylindrical body having therein three passages, two of which are straight and extend completely through the said body and the third of which is curved 35 inside the body and makes its exit from the same face of the said body at which it entered, a bearing shaft at the central axis of the said body, a closely fitting casing for the said body, the said casing being open at one end and closed at the other except for two holes 40 registerable with the straight passages through the body and a hole to receive the bearing shaft, and lever means to rotate the valve body in the casing, through an angle of 90°, and spring means cooperating with the lever 45 means to return the said valve body to its original position after release of pressure on the said lever means.

6. In combination with a musical wind 50 instrument in a valve, a cylindrical body having therein three passages, two of which are straight and extend through the said body and the third of which bends inside the body and makes its exit from the same face at 55 which it enters, a casing for said body, one end of which is closed except for two holes registerable with the straight passages, and one hole to receive a bearing shaft on the body, and means for revolving the body in 60 side the casing.

7. In combination with a musical wind instrument, in a valve, a cylindrical body having therein three passages, two of which are straight and extend completely through the 65 said body and the third of which is curved

inside the body and makes its exit from the same face of the said body at which it entered, a bearing shaft at the central axis of the said body, a closely fitting casing for the said body, the said casing being open at one end and closed at the other except for two holes 70 registerable with the straight passages through the body and a hole to receive the bearing shaft, and lever means to rotate the valve body in the casing. 75

8. In combination with a musical wind instrument, in a valve, a cylindrical body having therein three passages, two of which are straight and extend completely through the said body and the third of which is curved 80 inside the body and makes its exit from the same face of the said body at which it entered, a bearing shaft at the central axis of the said body, a closely fitting casing for the said body, the said casing being open at one end and closed at the other except for two holes 85 registerable with the straight passages through the body and a hole to receive the bearing shaft, and lever means to rotate the valve body in the casing, a squared portion 90 on the bearing shaft adapted to cooperate with a square hole in one of the levers whereby a connection between the lever and the valve body may be established. 90

9. In combination with a musical wind instrument, in a valve, a cylindrical body having therein three passages, two of which are straight and extend completely through the said body and the third of which is curved 100 inside the body and makes its exit from the same face of the said body at which it entered, a bearing shaft at the central axis of the said body, a closely fitting casing for the said body, the said casing being open at one end and closed at the other except for two holes 105 registerable with the straight passages through the body and a hole to receive the bearing shaft, and lever means to rotate the valve body in the casing, through an angle 110 of 90°. 110

10. In combination with a musical wind instrument, in a valve, a cylindrical body having therein three passages, two of which are straight and extend completely through the said body and the third of which is 115 curved inside the body and makes its exit from the same face of the said body at which it entered, a bearing shaft at the central axis of the said body, a closely fitting casing for the said body, the said casing being open at one end and closed at the other except for two 120 holes registerable with the straight passages through the body and a hole to receive the bearing shaft, and lever means to rotate the valve body in the casing through an angle of 125 90°, and spring means cooperating with the lever means to return the said valve body to its original position after release of pressure on the said lever means.

11. In combination with a musical horn 130

having crooks, in a valve, a cylindrical body having therein three passages, two of which are straight and extend through the said body and the third of which bends inside the body and makes its exit from the same face at which it enters, a casing for said body, one end of which is closed except for two holes registerable with the straight passages, and one hole to receive a bearing shaft on the body, and means for revolving the body inside the casing.

12. In combination with a musical horn having crooks, in a valve, a cylindrical body having therein three passages, two of which are straight and extend completely through the said body and the third of which is curved inside the body and makes its exit from the same face of the said body at which it entered, a bearing shaft at the central axis of the said body, a closely fitting casing for the said body, the said casing being open at one end and closed at the other except for two holes registerable with the straight passages through the body and a hole to receive the bearing shaft, and lever means to rotate the valve body in the casing.

13. In combination with a musical horn having crooks, in a valve, a cylindrical body having therein three passages, two of which are straight and extend completely through the said body and the third of which is curved inside the body and makes its exit from the same face of the said body at which it enters, a bearing shaft at the central axis of the said body, a closely fitting casing for the said body, the said casing being open at one end and closed at the other except for two holes registerable with the straight passages through the body and a hole to receive the bearing shaft, and lever means to rotate the valve body in the casing, a squared portion on the

bearing shaft adapted to cooperate with a square hole in one of the levers whereby a connection between the lever and the valve body may be established.

14. In combination with a musical horn having crooks, in a valve, a cylindrical body having therein three passages, two of which are straight and extend completely through the said body and the third of which is curved inside the body and makes its exit from the same face of the said body at which it entered, a bearing shaft at the central axis of the said body, a closely fitting casing for the said body, the said casing being open at one end and closed at the other except for two holes registerable with the straight passages through the body and a hole to receive the bearing shaft, and lever means to rotate the valve body in the casing, through an angle of 90°.

15. In combination with a musical horn having crooks, in a valve, a cylindrical body having therein three passages, two of which are straight and extend completely through the said body and the third of which is curved inside the body and makes its exit from the same face of the said body at which it entered, a bearing shaft at the central axis of the said body, a closely fitting casing for the said body, the said casing being open at one end and closed at the other except for two holes registerable with the straight passages through the body and a hole to receive the bearing shaft, and lever means to rotate the valve body in the casing through an angle of 90°, and spring means cooperating with the lever means to return the said valve body to its original position after release of pressure on the said lever means.
